CHARLES C. ABBOTT, OF PITTSFIELD, MASSACHUSETTS, ASSIGNOR TO TRIUMPH VOTING MACHINE COMPANY, OF PITTSFIELD, MASSACHUSETTS, A CORPORATION OF NEW JERSEY.

GROUPING MECHANISM FOR VOTING-MACHINES.

No. 873,400.

Specification of Letters Patent.

Patented Dec. 10, 1907.

Application filed May 20, 1907. Serial No. 374,612.

To all whom it may concern:

Be it known that I, CHARLES C. ABBOTT, a citizen of the United States, residing at Pittsfield, county of Berkshire, State of Massachusetts, have invented a new and useful 5 Grouping Mechanism for Voting-Machines, of which the following is a specification.

This invention relates to that portion of the mechanism of a voting machine that has 10 to do with group voting, so called.

The invention is shown as applied to a "horizontal" machine, in which the names of party candidates are placed in horizontal lines and the names of all candidates for the 15 same office are placed in vertical columns. But the invention is, of course, equally applicable to a "vertical" machine, in which the names of party candidates are placed in vertical columns and the names of all candidates for the 20 same office are placed in horizontal lines, or to a machine in which the names of candidates for each office are placed in alphabetical order without party columns.

The invention consists in certain constructions and in certain parts, improvements and combinations which adapt a voting machine for group voting, and that will permit votes to be cast in a group in accordance with the will of the voter, all for the nominees of one 25 party, or for one nominee of each party, or for any number of nominees of any party up to the total number of offices in a group and will furthermore render it impossible for a voter to cast but one vote for any candidate, 30 or more votes than there are offices in a group.

With these and other objects in view I have devised the novel grouping mechanism which I will now describe, referring to the accompanying drawing forming a part of this 35 specification and using reference characters to indicate the several parts:

Figure 1 is a front elevation of so much of the mechanism of a voting machine as is required to illustrate my present invention, 45 certain of the parts being shown in vertical section; and Fig. 2 is a vertical section on the line 2—2 in Fig. 1, looking in the direction of the arrows.

50 10 denotes the base of a voting machine, 11 the front plate, 12 an intermediate plate, 13 the grouping plate which is U-shape in cross section and is shown as rigidly secured to the front and intermediate plates by studs 55 14 which also serve as journals for rollers 15

which I term for convenience the fixed grouping rollers.

16 denotes voting members shown as journaled in the front and intermediate plates, and each comprising, so far as the present invention is concerned, a shaft specifically indicated by 17, a voting lever indicated by 18 and a depressing arm indicated by 19.

20 denotes interlocking members as a 65 whole. These interlocking members correspond in number with the lines of voting members and each comprise side plates 21 and cam plates 22 movable obliquely relatively to the side plates. The cam plates in 70 each interlocking member correspond in number with the voting members in a vertical column. When a voting member is operated the depressing arm 19 of the voting member engages the corresponding cam 75 plate of the interlocking member and displaces it laterally, as shown by the lower cam plate in the second interlocking member, the effect of which is to contract the interlocking member longitudinally by placing a slack 80 therein.

In setting up the machine for regular voting, one voting member corresponding with each interlocking member is operated, thereby placing a slack in the interlocking member, which is then so set that no further slacks can be placed therein, thereby rendering it impossible for any voter to vote for but one candidate for any office. The interlocking members pass through slots 23 in 85 longitudinal braces 24 shown as riveted to the intermediate plate. These braces serve as guides and supports for the interlocking member, the slots being made amply long to permit the required lateral movement of the 90 cam-plates. When a depressing arm is moved to the operative or voting position (see lower depressing arm in second column), it will be noted that it swings slightly past the center, so as to be self-retaining in the 95 voting position, and rests against a longitudinal brace which serves as a stop therefor.

25 denotes rollers which I term the connecting member rollers and which are pivoted between the lower ends of the lower side 100 plates of the interlocking members.

26 denotes flexible connecting members, in the present instance chains. One end of each connecting member is shown as pivoted to a link 27 which in turn is pivoted to a stud 110

28, shown in the present instance as projecting from the intermediate plate. Each flexible connecting member passes over one of the connecting member rollers and has pivoted at its other end a carrier 29 in which is pivoted a grouping roller 30. These rollers I term for convenience movable grouping rollers.

31 denotes the flexible grouping member, 10 in the present instance a chain, which passes alternately about the movable and fixed grouping rollers, as clearly shown. The ends of the flexible grouping member are connected to some fixed portion of the machine, 15 in the present instance to the base. I preferably interpose a turn buckle 32 between the grouping member and its point of attachment at one or both ends in order to provide adjustment for the flexible grouping member 20 in setting up the machine and to take up the slack in use.

In ordinary voting, the flexible grouping member is locked to each of the fixed grouping rollers by means of shoes 33 which are 25 pivotally connected to screws 34 which engage the horizontal portion of the grouping plate. Openings 35 are provided near the lower end of the intermediate plate in order to give access to the heads 36 of the screws 30 to set or release the shoes. It will be understood, of course, that in voting machines as ordinarily constructed, for example, in the Triumph voting machine, the other end of each interlocking member (not shown) is 35 connected to the corresponding portion of the independent voting mechanism (not shown, as it forms no portion of the present invention). In the normal position of the parts—that is, when no voting member has 40 been operated—the interlocking members will be at their elongated position and the connecting member rollers and the carriers will be at their lowered position (see first and third columns in Fig. 1). When a voting 45 member is operated, a slack will be placed in the corresponding interlocking member and said member will be contracted, raising the connecting member roller and carrier, as, for example, the second interlocking member as 50 in Fig. 1.

The operation is as follows: In setting up the machine for ordinary voting one slack is placed in each interlocking member by operating one voting member corresponding 55 therewith; then the flexible grouping member is tightened up so as to leave no slack therein. For ordinary voting, as already stated, the flexible grouping member is locked upon each fixed grouping roller by 60 moving the corresponding shoe 33 tightly against it, thereby locking the chain to the roller so that there can be no movement of either. The rule for setting up the machine for group voting is simply to loosen all of the 65 shoes 33 between the first and last columns

in a group. Suppose, for example, that the three interlocking members illustrated were to be grouped—that is to say, that a voter is to be permitted to vote for three candidates for the same office—the officials having the 70 election in charge would turn the screws 34 backward and release the grip of the shoes 33 upon the flexible grouping member so that it would be no longer locked to the fixed grouping rollers, the released position of the shoes 75 being indicated by dotted lines. As three candidates are to be voted for it is necessary that provision be made for casting the three votes all in one column, or two in one column and one in either of the others, or, if a voter 80 so elect, one in each of the columns. In other words, it is necessary to make the slacks transferable. This is effected by loosening the shoes 33, as indicated in dotted lines, so that the slacks may be transferred 85 from one interlocking member to another by means of the flexible connecting members and the flexible grouping member. To set up the machine again for ordinary voting, one voting member corresponding with each 90 interlocking member would be operated and then the shoes 33 would be tightened up, locking the flexible grouping member again to the fixed grouping rollers, as already explained. 95

It will, of course, be obvious that the amount of movement of a flexible connecting member in the direction of its length when the corresponding interlocking member is operated by a voting member will be double 100 the longitudinal contracting movement of the interlocking member, and that the movement of the flexible grouping member in the direction of its length will be twice the movement of the flexible connecting member in 105 the direction of its length, or four times the longitudinal contracting movement of the interlocking member, the principle being simply that of the differential pulley. The special object of this construction is to secure 110 a relatively great movement of the flexible grouping member in the direction of its length by means of a relatively small longitudinal contracting movement of the interlocking members. By so doing I render it 115 practically impossible to produce sufficient strain upon the flexible grouping member to enable a voter to cast an additional or fraudulent vote. This feature of construction becomes of especial importance when a relatively large number of columns are included 120 in a group.

Having thus described my invention, I claim:

1. In a voting machine, the combination 125 with voting members and interlocking members having rollers, of fixed grouping rollers, carriers having movable grouping rollers, a flexible grouping member passing alternately about the fixed and movable grouping 130

rollers and flexible connecting members attached to the carriers and passing over the rollers on the interlocking members and attached to a fixed portion of the machine.

5 2. In a voting machine, the combination with voting members and interlocking members having rollers, of fixed grouping rollers, carriers having movable grouping rollers, a flexible grouping member passing alternately about the fixed and movable grouping rollers, flexible connecting members attached to the carriers and passing over the rollers on the interlocking members and attached to a fixed portion of the machine, and means for locking the flexible grouping members upon the fixed grouping rollers for ordinary voting.

10 3. In a voting machine, the combination with interlocking members having rollers, a grouping plate and fixed grouping rollers journaled therein, of flexible connecting members passing over the rollers in the interlocking members, carriers attached thereto and carrying movable grouping rollers, a flexible grouping member passing alternately about fixed and movable grouping rollers, screws in the grouping plate and shoes carried thereby which are adapted to lock the flexible grouping member to the fixed grouping rollers intermediate the first and last

15 30 columns in a group.

4. In a voting machine, the combination with interlocking members having rollers, a grouping plate and fixed grouping rollers journaled therein, of flexible connecting members passing over the rollers in the interlocking members, carriers attached thereto and carrying movable grouping rollers, a flexible grouping member passing alternately about fixed and movable grouping rollers,

35 40 means for adjusting the flexible grouping

member, and means for locking the flexible grouping member to the fixed rollers.

5. In a voting machine, the combination with interlocking members, fixed grouping rollers and carriers having movable grouping 45 rollers, of flexible connecting members having engagement with the interlocking members and attached to the carriers, a flexible grouping member passing alternately about a fixed and movable grouping roller and 50 means for locking the flexible grouping member to the fixed grouping rollers.

6. In a voting machine, the combination with interlocking members, fixed grouping rollers and carriers, of flexible connecting 55 members having engagement with the interlocking members and attached to the carriers, a flexible grouping member passing alternately about a fixed grouping roller and through a carrier and means for locking the 60 flexible grouping member to the fixed grouping rollers.

7. In a voting machine, the combination with interlocking members, a U-shaped grouping plate, fixed grouping rollers journaled therein and carriers, of flexible connecting members having engagement with the interlocking members and attached to the carriers, a flexible grouping member passing alternately about a fixed grouping 70 roller and through a carrier, screws in the grouping plate and shoes carried by said screws for locking the flexible grouping member to the fixed grouping rollers.

In testimony whereof I affix my signature, 75
in presence of two witnesses.

CHARLES C. ABBOTT.
